UNITED STATES PATENT OFFICE

PERCY A. ROBBINS, OF HIGHLAND PARK, ILLINOIS

SOUND RECORDING DEVICE

Application filed September 19, 1930. Serial No. 482,994.

This invention relates to the production of sound records which may be divided as required, stored in small space, are not injured by handling, and are particularly adapted for use as a substitute for the delicate wax cylinders commonly employed as dictograph records. Records of this type are shown and described in my co-pending applications Nos. 445,781 and 445,782, dated April 19th, 1930, and the object of the present invention is to provide simple and efficient apparatus for mechanically producing such records.

I attain my object by utilizing a travelling flexible ribbon as a diaphragm adapted to be vibrated, by sound waves concentrated thereon by means of a suitable horn, against a cutting tool adapted to engrave the surface of the travelling ribbon in accordance with the frequencies of the sound waves impinging thereon. A record so produced will have the required characteristics and, according to the nature of its material may be used to reproduce the recorded sound in known ways.

A typical form of my invention is illustrated in the accompanying drawings in which

Fig. 1 is a front elevation partly in section, the driving means being omitted;

Fig. 2 a perspective view of a modification; and

Fig. 3 a vertical section through the throat of the horn looking towards the travelling ribbon.

In the drawings like numerals of reference indicate corresponding parts in the different figures.

Referring to Fig. 1 of the drawings, 1 is a frame suitably shaped to support the different parts. On this frame is pivotally supported, preferably removably, the storage reel 2 carrying a roll of flexible record ribbon 3. This record ribbon may be such a ribbon as is shown and described in my co-pending application No. 445,782; that is, a flexible film which will pass light rays in proportion to the extent to which its surface is engraved by a cutting tool and which may be either a thinning of the material, the production of engraved areas of varying extent, or both. If, however, the record is to be re-

produced by the mechanical operation of a stylus, the quality of translucency is not required. In any case, however, the ribbon must possess the quality of vibrability under the action of sound waves as it is expected to serve as an acoustic diaphragm. The ribbon passes around suitable guide rollers 4 and 5, thence passing to the feed rollers 6 and 7 which are geared together by means of the gears 8 and 9. One of these gears is provided with a driving shaft 10, which may be driven in any suitable manner. An adjustable friction brake 11 of known type is provided whereby the ribbon may be tensioned to any extent necessary.

Behind the ribbon is located a rotary cutter 12, which may be a fine toothed milling cutter. This cutter is secured to a shaft 13 journalled in the frame 1 and provided with the pulley 14 by means of which the cutter may be driven at any desired speed by any suitable motor.

15 is a horn which may be of any suitable type adapted to collect atmospheric sound waves and to cause them to impinge on the travelling ribbon 3. To design a suitable shape of horn for this purpose and to properly load the ribbon diaphragm is within the scope of anyone skilled in the art. When the cutter and ribbon are in motion, as hereinbefore described, and sound waves are collected by the horn, the ribbon 3 being under tension vibrates as a diaphragm and engages the revolving cutter 12. A sound trace is thus engraved on the ribbon surface, as in the co-pending application hereinbefore referred to, and the engraved record thus obtained may be used to reproduce sound as referred to in the preamble to the specification.

In Fig. 2 of the drawings a slight modification is shown. A pair of rollers 5^a replaces the roller 5 and a pair of guide rollers 16 is added adjacent the horn 15. The rollers 5^a and 16 may be positioned to limit the length of the ribbon vibrating as a diaphragm as may be found desirable.

The shaft 13 of the rotary cutter 12 is positioned horizontally and the guide rollers 5^a and 16 are positioned to guide the ribbon diagonally past the edge of the cutter, which is

thus adapted to engrave the ribbon as the latter is moved past it.

The cutter shaft is journalled on a slide 17 movable on the guides 18 to-and-from the ribbon and an adjusting screw 20 is provided whereby the slide may be adjusted to bring the cutter and ribbon into the proper position for co-operation. The rollers 6 and 7 are shown as driven by worm gearing 19.

10 What I claim as my invention is:

1. Apparatus for making sound traces on sound records comprising a continuously-moving driven cutting element; means for moving a flexible vibratile record ribbon

15 past the cutting element with one of its flat surfaces presented to the cutting element within the limits of vibration of the ribbon; and means for directing atmospheric sound waves against the record ribbon to cause a

20 cutting engagement between the record ribbon and the cutter to produce a sound trace corresponding to the sound waves.

2. Apparatus for making sound traces on sound records comprising a continuously-

25 moving driven cutting element; means for moving a flexible vibratile record ribbon past the cutting element with one of its flat surfaces presented to the cutting element within the limits of vibration of the ribbon;

30 and a horn having its throat positioned in proximity to the record ribbon whereby the latter forms a diaphragm for the horn and is caused to effect a cutting engagement between itself and the cutting element to produce a sound trace corresponding to sound waves received by the horn.

3. Apparatus for making sound traces on sound records comprising a continuously-moving driven cutting element; means for

40 moving a flexible vibratile record ribbon past the cutting element with one of its flat surfaces presented to the cutting element within the limits of vibration of the ribbon; adjustable means for tensioning the record

45 ribbon; and means for directing atmospheric sound waves against the record ribbon to cause a cutting engagement between the record ribbon and the cutter to produce a sound trace corresponding to the sound waves.

50 4. Apparatus for making sound traces on sound records comprising a continuously-moving driven cutting element; means for moving a flexible vibratile record ribbon past the cutting element with one of its flat

55 surfaces presented to the cutting element within the limits of vibration of the ribbon; adjustable means for tensioning the record ribbon; means for directing atmospheric sound waves against the record ribbon to

60 cause a cutting engagement between the record ribbon and the cutter to produce a sound trace corresponding to the sound waves; and means for adjusting the cutter to-and-from the surface of the ribbon.

65 5. Apparatus for making sound traces on

sound records comprising a continuously-moving driven cutting element; a flexible vibratile record ribbon mounted to travel past the cutting element with one of its flat surfaces presented to the cutting element with- 70 in the limits of vibration of the ribbon; and means for vibrating the ribbon in a direction normal to the said flat surface in correspond- ence with sound waves.

Signed at Highland Park, Ill., this 28th 75 day of August, 1930.
